UNITED STATES PATENT OFFICE.

ARCHIE F. NAIR AND HOBERT A. NAIR, OF GLENDALE, CALIFORNIA.

BOMBER ATTACHMENT FOR AEROPLANES WITH GAS BOMBS.

Application filed July 30, 1927. Serial No. 209,596.

Our invention relates to a bomber attachment for aeroplanes with a novel gas bomb, it being an especial object of our invention to provide a mechanism whereby the bomb may 5 be readily and quickly released when desired from the aeroplane and to provide means for supporting the bomb in convenient position to the engine of the aeroplane.

We attain these and other objects of our 10 invention by the mechanism illustrated in the accompanying drawings, in which—

Figure 1 is a side elevation of an aeroplane with our attachment mounted on same;

Fig. 2 is a vertical longitudinal section on 15 line 2—2 of Fig. 3;

Fig. 3 is a top plan view from a plane approximately on line 3—3 of Fig. 2.

Fig. 4 is a vertical section through the attachment with the gas bomb shown in end elevation on the line 4—4 of Fig. 3; and

Fig. 5 is a view of the attachment in operative position releasing the bomb from the attachment.

Like characters of reference designate like 20 parts in each of the several views.

Referring to the accompanying drawings, we utilize the longerons 1 and the landing chassis struts 3, and provide bolts 2 secured to and supporting the preferably cone-shaped 25 bomb holding frame 5, the disc-like forward end 6 of this frame being secured by bolts 2' to the braces 7. We provide a pivotally mounted bomb discharging forked arm 8 mounted on the pivot support 9. Any suitable means to be engaged by the free ends 30 of pivot arm 8 may be provided, such as the studs 14 as shown in Fig. 3, these studs projecting beyond the walls of the bomb to which they are affixed, sufficiently to be engaged by 35 the ends of arm 8. This arm is pivotally connected by a link 10 with the dump tilt control lever 11 which in turn is provided with an operating handle 12. Link 10 has an extension 27 which overlaps the operatively connected portion of the dump tilt control lever 11 to prevent the link and lever from dropping beyond the point of contact of extension 27 with member 11 as will be understood by 40 reference to Figs. 2 and 5.

It is within the contemplation of our invention to provide a suitable truck (not shown) on which the bomb-holding frame is supported and which will permit of convenient wheeling of the bomb holding frame to

a position where it can be readily attached to 55 the aeroplane.

Referring to Fig. 2 we provide the main torpedo 13 within which is contained a small torpedo 24 which is set off by a time fuse 15 when the device is to be used as a time bomb. 60 We also provide a poison gas chamber 23 in contact with which is a percussion member 20 and in contact with this percussion member 20 is a firing pin 21 carried by the slideable firing bolt 16 which bolt carries a bolt head 65 25 preferably of the shape shown in Fig. 2 and which will function to operate the device, destroy the bomb and release the gas if the device is dropped from an aeroplane onto the ground. We also provide a detachable cap 70 17 on the end of the poison gas chamber 23 to permit of filling the bomb with gas.

The end cap or cover 22 of main torpedo 13 is held in place by lock bar 19, which in turn is releasably engaged by the spring hooks 18, 75 the ends of which are fastened to the outer walls of the main torpedo by any suitable means such as the fastening members 26. The device may be operated either as a bomb 80 to be discharged by contact of the head of the firing bolt with any object when the bomb is dropped from an aeroplane; or it may be utilized as a time bomb to be discharged at a pre-determined time after being disposed in a location governed by the length of time the 85 time device 15 requires to discharge the small torpedo 24 and that in turn discharge the main torpedo 13 and thereby release the poison gas in the sealed container 23.

The method of operating the bomb when 90 carried by aircraft is to turn the nose of the aircraft upward and to release the bomb rearwardly from its casing or holder by the operation of handle 12, dump tilt control lever 11, link 10 and by the swinging movement of 95 pivot forked arm 8 is shown in Fig. 5 in which illustration the bomb is shown in the position as it is about to be discharged. The ends of the forked arm 8 are operatively connected with studs affixed to the walls of the 100 bomb so that movement of the arm will discharge the bomb from its normal position in the cone-shaped holding frame 5.

It is one of the purposes of our invention to provide a type of bomb which will effectively 105 destroy the bomb so that no one may see how it is made.

It is within the contemplation of our in-

vention to apply this attachment to any aircraft, such as a dirigible as well as to aeroplanes.

What we claim is—

- 5 1. In a bomber attachment for aircraft, the combination of a bomb holding frame open at one end, means for rigidly attaching such frame to an aeroplane, a pivotally mounted bomb-engaging member arranged
- 10 to discharge the bomb longitudinally of the frame from the open end thereof, and a manually operated lever operatively connected with said bomb-engaging member.
- 15 2. In a bomber attachment for aircraft, the combination of a cone-shaped bomb holding frame suspended beneath the aircraft, means for rigidly attaching said frame to the aircraft, a bomb-discharging member operatively engaging the bomb and arranged for
- 20 discharging the bomb longitudinally of the bomb holding frame from its open end, and a manually operated lever operatively connected with the free end of said bomb discharging member for actuating same to discharge the bomb.
- 25 3. In a bomber attachment for aircraft, the combination of a bomb receiving frame,

means for rigidly attaching said frame to aircraft beneath and longitudinally of the aircraft, the aforesaid bomb receiving frame 30 being of frusto-conical shape to receive a bomb of corresponding shape, a bomb discharging forked arm pivotally mounted on the aircraft and engaging the bomb, a link connected to the free end of said arm, and a 35 manually actuated approximately L-shaped lever connected with said link, the link having an extension adapted to engage the lever and prevent the link and lever from dropping from an aligned position.

4. In a bomber attachment for aircraft, the combination of a bomb receiving frame, means for rigidly attaching said frame to the frame work of aircraft, a bomb discharging mechanism, comprising a bifurcated pivoted arm having its ends engaging opposite portions of the bomb, a link connected to the actuated end of the arm, a dump tilt control lever pivotally mounted on the frame work of the aircraft and operatively connected with the aforesaid link, for causing the discharge of the bomb from the bomb receiving frame.
